UNITED STATES PATENT OFFICE.

GEORGE A. KOHOUT, OF CHICAGO, ILLINOIS.

FURNACE.

Application filed July 19, 1926. Serial No. 123,381.

My invention relates to furnaces together with a method of operating such furnaces, and has for its object the provision of a new method which is adapted to bring about the efficient combustion of fuel such as for instance coal, but which consists of particles having different sizes.

My invention also concerns itself with the provision of means which may be operated in accordance with my improved method.

The prime object of the invention is the provision of an arrangement whereby certain of the combustible elements of the fuel are acted upon while in suspension and caused to be maintained in this condition and violently agitated, prior to, during and after ignition, the heavier portions of the fuel being properly distributed over the grate and the gases emanating from the burning of this last mentioned fuel to be also violently agitated and mixed with the moving, ignited, suspended combustible material to further assist in spreading and flame propagation to thereby result in the complete consumption of all the combustible elements of the fuel, the elimination of smoke and the obtaining of the maximum heat from a given quantity of fuel.

My present invention concerns itself when applied to the burning of coal more particularly with the combustion of such coal in mixed sizes, that is, from fine powder to approximately nut size. In accordance with my invention, therefore, I may use what are in general referred to as standard screenings, which is the cheapest form of coal and which contains approximately fifty (50) per cent of fines with about fifty (50) per cent of nut and pea coal and intermediate sizes.

The general plan of operation is to have the fines burned more or less completely in suspension and to spread the larger coal over the entire grate area more or less in accordance with the weight of the particles, that is, the larger sizes fall near the front of the grate and the size of the particles gradually decreases toward the rear of the grate. In this way the fuel bed remains porous as the fuel bed itself is composed of large particles of a more or less regular shape so that the combustion rate is increased due to this lowering of the fuel bed resistance to the incoming air. This permits the use of a smaller combustion chamber than would be required where pulverized coal exclusively is to be burned.

The invention contemplates means whereby the coal is caused to pass a suitable fluid blast which may be either an air blast or a steam blast, or a combination of air and steam, or whatever would be serviceable, and this blast distributes the coal and causes the smaller particles thereof to be held in suspension, agitated and ignited while in suspension, and the larger portions to be distributed over the grate. This eliminates the large fuel bed resistance in the coking pile where the coking process is more largely used than with my improved device. The coal is in reality zoned and placed where it will be most readily consumed, depending upon its size.

The invention also contemplates a structure having the above qualifications and its combination with a coking shelf, and also the provision of a structure in which the shelf or abutment upon which the coal is supported prior to its introduction to the fire box of the furnace, is maintained in a relatively cool condition so that coking at this point will be prevented.

My improved furnace can, of course, be operated in many different ways and is not limited to the use of the method of operation which I have elaborated.

The drawings illustrate various forms of which the invention is susceptible, it being therefore obvious that various other combinations of elements and arrangements may be resorted to without departing from the spirit of the invention as defined in the appended claims forming a part hereof.

Fig. 1 is a longitudinal vertical section of a furnace constructed in accordance with one embodiment of the invention;

Fig. 2 is a horizontal sectional view taken on line 2—2 of Fig. 1;

Fig. 3 is a detail sectional view similar to Fig. 1, showing a part of the structure illustrated in Fig. 1 combined with an auxiliary fluid inlet and means for regulating the amount of air which enters the furnace through the fluid passage shown in Fig. 1;

Fig. 4 is a plan view similar to Fig. 2, showing a blower connected with the fluid passages for introducing air under pressure to the fire box of the furnace;

Fig. 5 is a sectional plan view similar to Fig. 2, showing the use of steam jets for the purpose of distributing the fuel and agitating a portion thereof and the combustible gases of the ignited fuel;

Fig. 6 is a sectional view similar to Fig. 2, showing an arrangement employing both air and steam to accomplish the desired result;

5 Fig. 7 illustrates a means for controlling the period of operation of the fluid inlets;

Fig. 8 is a detail elevation of an air regulator shown in Fig. 3;

10 Fig. 9 discloses a hopper located above the furnace and a blast opening and fuel feed opening arranged relatively to each other to accomplish the desired result;

15 Figs. 10 and 11 show structures whereby the smaller particles of the fuel are directed toward the upper part of the combustion chamber and the larger parts distributed over the grate.

20 The structure with which the various forms of the invention are applicable includes a furnace comprising a combustion chamber 10 surmounted by the boiler 11 and circumscribed by the rear walls 12, the grate 13 and the front wall consisting of a plurality of parts presently to be explained more in detail. The passageway 14 leads to the stack, and the grate 13 may be of the stoker grate or any other variety. The grate consists in the present disclosure of a plurality of swingingly mounted elements such as the elements 30 15, all of which are movable to advance the fuel along the grate when actuated by the handle 16 which handle is associated with said grate sections through the agency of the link 17 and the connecting rod 18.

35 A pair of dumping plates 19 and 20 are provided as heretofore and these are operable through the agency of the dumping bar 21. The ash pit is shown at 22 and the floor level at 23. In the front of the furnace I provide a reverberatory section 24 made of fire brick below which there is a fuel inlet opening 25 at the lower portion of which is placed a fuel resting shelf 26 forming part of the front wall and which preferably extends 40 down to the floor line, there being an opening 27 in this front wall closed by a door 28, through which refuse may be introduced for burning or for access to the interior of the combustion chamber for other purposes. A 45 fuel hopper 29 is provided into which the fuel is fed and from which it progresses toward and into the combustion chamber. I provide pushers 30 which periodically advance the fuel and which may during the 50 period of their movement entirely close the opening between the fuel hopper and the fuel resting shelf. These pushers are automatically or manually operated in any suitable manner, as by the hand lever 31. As is readily apparent, of course, there may be a plurality of levers 16, depending upon the width of the furnace so that the grate may be divided into sections; there may be a plurality of doors 28 and there may be a plurality of

pushers 30, all depending upon the size and width of the furnace.

55 In accordance with one form of my invention, as shown in Fig. 1, I provide a duct 32 below the fuel resting plate. This duct connects with a suitable source of supply typified by the chamber 33 through which duct an air blast, a steam blast, or a combination of both, or any other constant or intermittent desirable blast may be introduced into the furnace. There may, of course, be any number of such ducts 32 arranged throughout the width of the shelf 26 so as to carry out the principle and method of my invention.

60 As before stated, the object of the invention is capable of being obtained through the use of a fluid such as either air or steam, or a combination of both. The structure just described contemplates the utilization of air heated by the heat of the side walls and introduced to the fire box through the chamber 33, and the ducts 32. The chamber 33 is as shown, connected with one or more air passages 36 respectively provided in the side walls of the furnace which passages communicate with the atmosphere, and due to the relative difference of pressure at one end of the passage over that pressure at the opposite end, the portions of the fuel as they pass across the passage are caused to be separated, distributed and agitated in the manner referred to.

65 It is manifest that a blower 37 (Fig. 4) may be connected with said passages 36 and that also said passages may be controlled through the medium of damper regulators 38-38, 100 provided in each passage.

70 The fuel which may be burned in a furnace of this kind and which gives very good results is coal which is commercially denominated as screenings. This consists of coal of various sizes from coal dust to egg and nut size, together with all of the intermediate sizes. According to my improved method, the mechanism automatically zones this fuel so that it is deposited at different 105 points within the combustion chamber depending upon its size. I have shown a fuel bed 34 upon the grate and as will be noted the fuel bed is thicker at the front of the furnace and thinner to the rear. The larger lumps of coal fall toward the front of the furnace immediately below the fuel resting shelf and from there on the coal becomes smaller toward the rear of the grate. During the course of the combustion, the coal may be advanced upon the grate if desired so that finally the ash which settles upon the plates 19 and 20 may be dumped. The finely divided coal is blown by the jet in a more or less horizontal direction into the zone in the intense combustion above the fuel bed where it is consumed in a manner to give maximum efficiency. In this manner the coal is graded 110

so that each particular size is burned under the conditions of maximum efficiency. The finely divided coal is burned in suspension, agitated and caused, due to its agitation, to mix with the gases emanating from other fuel in the combustion chamber. The larger particles are deposited in the thicker mass and may travel throughout the full length of the grate during the period. The smaller particles rearwardly are given less time to complete the combustion.

When an arrangement employing both air and steam as the medium for distributing the fuel in the manner described, is utilized, the pipe connections such as 52 in Fig. 3, conveniently provide a means whereby to support a regulator to regulate the amount of air passing through the air passage 53. The means shown consists of a plate 49 which is rotatably adjustable along each of the pipe sections by means of the threaded connection between the pipe and said plate to thereby when rotated vary the distance between the adjacent extremity of the air passage and the plate, and regulate the quantity of air entering said air passage. This plate is further provided with a plurality of apertures 50 whereby a certain amount of air will at all times be permitted to enter the passage even though the plate is arranged to close the passage.

An alternative construction which may be resorted to, to accomplish the desired end, is shown in Fig. 5, in which steam only is utilized to distribute the fuel and accomplish the various other previously referred to features of the invention. In this construction a header 39 having a desired number of pipe extensions 51 connected therewith, is employed and arranged to discharge into the fire box of the furnace and may be arranged below the fuel support 26 illustrated in Fig. 1. It is manifest that an arrangement such as illustrated in Fig. 6 may also be employed. In the last named arrangement the fuel is caused to be distributed in the hereinbefore described manner by means which employs the combination of both air and steam, and may when found desirable, introduce steam under pressure to the fire box by means of the pipe extensions 52', the air being drawn through the open ends of the openings 53' by virtue of the reduced pressure existing at that end of the opening 53' adjacent the fire box and pipe connection 52' having the nozzle 54. It is of course understood that the pipe sections 52' are connected to a source of steam supply such as the pipe indicated at 55.

Fig. 7 illustrates a means whereby an intermittent instead of a constant discharge of one of the fluids may be obtained so that the fluid is intermittently fed to the furnace. This means includes a cam 65 carried by the shaft whereby the pushers 30 are operated. This cam has a part which engages the valve arm

66 which is held against the cam by means of a spring 67. The cam face is such that the valve will be automatically and quickly opened during the period of operation of the pushers and held open a suitable time and then quickly closed.

In Fig. 9 the arrangement includes a fuel hopper 80 and fuel feed 81, an opening 82 arranged in the upper wall of the furnace, an air passage 83 and steam passage 84 located relatively to each other so that as the fuel is fed through the opening 82 it drops in front of the passages 83 and 84 and is spread in the manner described and causes the finer particles of the fuel to be retained in suspension during combustion.

Figs. 10 and 11 both disclose a construction in which the fluid acts upon the smaller particles of the fuel to direct them towards the upper part of the combustion chamber, cause them to be held in suspension, and whirled while in suspension.

To accomplish this end the fluid passage may be either provided with means or the passage may be arranged so that the fluid will be directed in a manner to result in this action of the fluid. In the structure disclosed in Fig. 10 the fluid passage 70 is arranged in an air passage 71 and an end of the fluid passage 70 is formed to provide a jet having the plate or extension 72 which is inclined upwardly and acts as a spreader for the fluid as it strikes the plate. The plate causes the fluid to be directed upwardly, forwardly and sidewise, and consequently causes the finer particles of fluid to be distributed in a corresponding manner.

The structure illustrated in Fig. 11, one termination of the air passage 73 is inclined upwardly and the adjacent end of the fluid passage 74 is inclined in the same manner and therefore this arrangement will act upon the fuel in a manner similar to that described in connection with the structure shown in Fig. 10. It is of course understood that the fuel is caused to pass the fluid outlets and be acted upon while in suspension, so that the proper distribution of the fuel above and over the grates will result.

It is manifest that in all of the structures disclosed the blast is so arranged that the entire grate is properly covered so that there is no infiltration of air over uncovered grate sections. Such infiltration of air reduces the efficiency very materially.

From what I have thus described, the nature of my invention will be readily apparent to those skilled in the art and it will also be readily apparent that many other modifications may be made without departing from the spirit of my invention.

Having, however, thus described the invention, what I claim as new and desire to secure by United States Letters Patent is:

1. The herein described method of combus-

tion which consists in providing a source of fuel supply having coal of varying sizes, delivering the coal into a combustion chamber, subjecting the delivered coal to a blast there-
5 by separating and distributing said coal, blowing the more finely divided particles into the combustion zone where they are burned in suspension and supporting and burning the remainder of the coal in the lower
10 portion of said chamber.

2. The herein described method of combustion which consists in providing a source of fuel supply having coal of varying sizes, delivering said coal into a combustion chamber
15 above the bottom thereof so that it will fall freely within said chamber, subjecting the delivered coal while falling to a blast thereby separating and distributing said coal according to size, blowing the more finely divided
20 particles into the combustion zone where they are burned in suspension and supporting and burning the remainder of the coal in the lower portion of said chamber.

3. A furnace of the character described comprising a combustion chamber, a stoker grate, a fuel inlet near the forward end of said grate, and a fluid jet above the grate and in close proximity to said fuel inlet adapted to distribute the fuel over said grate in accordance with its size said fluid jet being the sole means for separating and distributing the fuel.

4. A furnace of the character described comprising a combustion chamber, a stoker grate, a fuel inlet near the forward end of said grate, and a fluid jet above the grate and in close proximity to said fuel inlet directed across the path of the fuel from the inlet to the grate to distribute the fuel over said grate
30 in accordance with its size and to retain the smaller particles of said fuel in suspension in the combustion zone.

5. A furnace of the character described comprising a combustion chamber, a stoker grate, a fuel inlet near the forward end of said grate, said fuel inlet terminating at a shelf, means for gradually advancing said fuel through said inlet so that it falls over the edge of said shelf, and a fluid jet above
45 the grate and in close proximity to said fuel inlet directed at substantially right angles to the path of the fuel to distribute the fuel over said grate in accordance with its size.

6. A furnace of the character described comprising a combustion chamber, a stoker grate adapted to feed material supported thereby toward the rear of the furnace, means for actuating said grate, a fuel inlet near the forward end of said grate, said fuel inlet
50 terminating at a shelf, means for gradually advancing said fuel through said inlet so that it falls over the edge of said shelf, and a fluid jet above the grate and in close proximity to said fuel inlet adapted to distribute
60 the fuel over said grate in accordance with its

size and to retain the smaller particles of said fuel in suspension in the combustion zone.

7. A furnace of the character described adapted to burn fuel consisting of particles of unlike dimensions, comprising a combustion chamber, a stoker grate, a fuel inlet near the forward end of said grate, said fuel inlet terminating at a shelf, means for gradually advancing said fuel through said inlet so that it falls over the edge of said shelf,
75 and a fluid jet above the grate and beneath said shelf adapted to separate the fuel while falling and distribute the fuel over said grate in accordance with its size.

8. A furnace of the character described, 80 adapted to burn fuel consisting of particles of unlike dimensions comprising a combustion chamber, a stoker grate, a fuel inlet near the forward end of said grate, said fuel inlet terminating at a shelf, means for gradually advancing said fuel through said inlet so that it falls over the edge of said shelf, and a fluid jet above the grate and beneath said shelf adapted to separate the fuel while falling and distribute the fuel
85 over said grate in accordance with its size, and to retain the smaller particles of said fuel in suspension in the combustion zone.

9. A furnace of the character described comprising a combustion chamber, a stoker grate, a fuel inlet near the forward end of said grate, said fuel inlet terminating at a shelf, means for gradually advancing the fuel through said inlet so that it falls over the edge of said shelf, a fluid jet above
95 the grate and in close proximity to said fuel inlet adapted to distribute the fuel over said grate in accordance with its size, means at one extremity of the grate for dumping the ash, and means for operating said
10 grate to advance the fuel toward the rear end thereof.

10. A furnace of the character described comprising a combustion chamber, a stoker grate, a fuel inlet near the forward end of said grate, said fuel inlet terminating at a shelf, means for gradually advancing the fuel through said inlet so that it falls over the edge of said shelf, a fluid jet above
11 the grate and in close proximity to said fuel inlet adapted to distribute the fuel over said grate in accordance with its size and to retain the smaller particles of said fuel in suspension in the combustion zone, means at one extremity of the grate for dumping the ash,
12 and means for operating said grate to advance the fuel toward the rear end thereof.

11. A furnace of the character described adapted to burn fuel consisting of particles of unlike dimensions, comprising a combustion chamber, a stoker grate, a fuel inlet near the forward end of said grate, said fuel inlet terminating at a shelf, means for gradually advancing the fuel through said inlet so
13 that it falls over the edge of said shelf, a

fluid jet above the grate and in close proximity to said fuel inlet adapted to distribute the fuel over said grate in accordance with its size, means at one extremity of the grate 5 for dumping the ash, and means for operating said grate to advance the fuel toward the rear end thereof.

12. A furnace of the character described adapted to burn fuel consisting of particles 10 of unlike dimensions comprising a combustion chamber, a stoker grate, a fuel inlet near the forward end of said grate, said fuel inlet terminating at a shelf, means for gradually advancing the fuel through said inlet 15 so that it falls over the edge of said shelf, a fluid jet above the grate and in close proximity to said fuel inlet adapted to distribute the fuel over said grate in accordance with its size and to retain the smaller particles 20 of said fuel in suspension in the combustion zone, means at one extremity of the grate for dumping the ash, and means for operating said grate to advance the fuel toward the rear end thereof.
- 25 13. In a furnace of the character described, a combustion chamber, a stoking grate, a

fuel inlet, a fluid inlet passage arranged with respect to the fuel inlet to cause the fuel to fall into the path of the fluid after its discharge from the fuel inlet to thereby distribute the fuel over the grate and maintain a portion of the fuel in suspension and means for actuating said grate to move the material thereon away from the fuel inlet.

14. The herein described method of combustion which consists in providing a source of fuel supply having coal of varying sizes, dropping the several sizes of coal into a combustion chamber together, subjecting the coal while falling within the chamber to a fluid 35 blast thereby separating the coarser from the finer particles of coal and distributing them according to size throughout the chamber burning the more finely divided particles in 40 suspension, burning the remainder of the coal 45 in the lower portion of the chamber and moving it away from the point of entry while burning.

In witness whereof, I hereunto subscribe my name this 8th day of July A. D., 1926.

GEORGE A. KOHOUT.
